(57) **CLAIM**

The ornamental design for a storage system and associated components set, as shown and described.

DESCRIPTION

FIG. 1 is a front and top side perspective view of a storage system and associated components set in an assembled state of use showing our new design;

FIG. 2 is a rear and bottom side perspective view of the storage system and associated components set of FIG. 1;

FIG. 3 is a rear view of the storage system and associated components set of FIG. 1;

FIG. 4 is a front view of the storage system and associated components set of FIG. 1;

FIG. 5 is a top view of the storage system and associated components set of FIG. 1;

FIG. 6 is a right side view of the storage system and associated components set of FIG. 1;

FIG. 7 is a left side view of the storage system and associated components set of FIG. 1;

FIG. 8 is a top perspective view of a first component of the storage system and associated components set shown separately for ease of illustration;

FIG. 9 is a bottom perspective view thereof;

FIG. 10 is a top perspective view of a second component of the storage system and associated components set shown separately for ease of illustration;

FIG. 11 is a bottom perspective view thereof;

(Continued)

FIG. 12 is a top perspective view of a third component of the storage system and associated components set shown separately for ease of illustration;

FIG. 13 is a bottom perspective view thereof;

FIG. 14 is a top perspective view of a fourth component of the storage system and associated components set shown separately for ease of illustration;

FIG. 15 is a bottom perspective view thereof;

FIG. 16 is a top perspective view of a fifth component of the storage system and associated components set shown separately for ease of illustration;

FIG. 17 is a bottom perspective view thereof;

FIG. 18 is a top perspective view of a sixth component of the storage system and associated components set shown separately for ease of illustration;

FIG. 19 is a bottom perspective view thereof;

FIG. 20 is a top perspective view of a seventh component of the storage system and associated components set shown separately for ease of illustration;

FIG. 21 is a bottom perspective view thereof;

FIG. 22 is a top perspective view of the second and third components of the storage system and associated components set in a state of sub-assembly, shown separately for ease of illustration;

FIG. 23 is a bottom perspective view thereof;

FIG. 24 is a top perspective view of a ninth component of the storage system and associated components set in a state of sub-assembly, shown separately for ease of illustration; and,

FIG. 25 is a bottom perspective view thereof.
